UNITED STATES PATENT OFFICE

ANGELO BELLONI, OF PORTOVENERE, ITALY

SUBMARINE RESCUE EMERGING COMPARTMENT

Application filed September 10, 1929, Serial No. 391,677, and in Italy September 30, 1928.

The present invention is intended to provide a solution of the problem of rescuing men from sunken submarines by a device such, that it would take the less possible weight and volume on board when cleared off, and that, needing no special change in the hull structures, can be easily applied to any type of submarine boat afloat.

The only essential idea of this device is that of getting the free water surface of the 10 air-lock (viz.: the water surface which undergoes an air-pressure equal to that of the water-pressure at that depth) in the inside compartment of the boat, by allowing water inrush from one of the ordinary deck hatchways, instead of getting it outside of the hull, by keeping the water just on the opening of a special heel hatchway.

Of course, the ways of carrying out such 20 an idea are different for the different forms of the compartments, where the deck hatchways open; and are also different, depending on whether the floor of these compartments is flooded or not; viz., whether the ship is a 25 sunken submarine or a rescuing one.

In the accompanying drawings:

Figure 1 shows one form of the invention in use with one type of compartment in the submarine (turret or conning-tower); and 30 Figures 2 to 7 show a second form for use with a different type of compartment (fore and aft torpedo rooms).

The first form of application, as disclosed in Fig. 1, is specially designed for use with 35 central- or turret-hatchways; and is an improvement on the "emerging room" shown in my prior British Patent No. 115,938/1918. It essentially consists in the employment of two thin iron plates, flat or rounded, designated 1 and 2, which are installed, permanently or not, in the conning-tower 3, or in a sufficiently wide double hatchway, as clearly shown by Fig. 1. It is advisable that the two ordinary doors or scuttles, 4 and 5, of the double hatchway, instead of being arranged vertically, one above the other, be situated the upper astern and the lower ahead (as in Fig. 1).

For rescuing purposes, all the surviving 50 men will be assembled together in the control-room 6, just under the conning-tower 3,

where the best trained man, equipped with a rescuing hood or respirator, will pass into the tower, through the opened hatchway 5. Both rooms or compartments 3 and 6 will be brought up to an air pressure equal to the water-pressure of that depth; the tub 8 will be flooded as high as the lower edge of plate 1 and when the spy-corks show the air pressure to be equal to the water pressure at the depth of the same lower edge of plate 1, 55 the man in the turret will begin opening the hatchway 4, which is pushed outwards by the excess of air-pressure. Water will rush in and air out of tube 7; until equilibrium will automatically be set between water and air. Then the hatchway 4 will be totally 60 opened; and the first man will be able to go out and emerge. After him, with no more trouble, all the other men can go out; dressed with hoods, if the submarine is lying more 65 than 10 fathoms; but without anything, if the depth is less. In this case, it will be sufficient that every man, standing in the water of the tub 8, keeps his breath before passing, by kneeling, into the room 7; whence he swims 70 to the surface. In the other case, of a greater depth, the men will be obliged to make some stops on the well-known signal buoy's rope, in order to avoid the caisson disease; or, better still, the transshipment to another rescuing 75 submarine, fitted with the same rescuing device which ought to be brought to bottom alongside; or, if the depth is very great, to be moored at the depth of first decompression stop. 80

For war purposes, evidently, the same device will enable to be sent out or taken in as many divers as necessary.

The second construction, shown by Figs. 2, 3, 4, 5, 6 and 7, is especially designed for use 85 with fore and aft hatchways; and is an improvement on the 1909 Lake "emerging room" disclosed in British Patent No. 4,639/1909. It consists essentially in the employment of a thin iron plate (preferably galvanized), which is ordinarily cleared off on the internal walls of the double hatchways or of the compartment below; and only when necessary 90 is rolled up as a tube and fastened watertight to the lower brass collar 20 of the 100

innermost scuttle of the double hatchway. Such an iron tube is much better than the flexible tube of the Lake patent, particularly when men are passing through it.

When the compartment 6 under the hatchway 3 is liable to be or must be flooded, as it happens in the sunken boat if it is not horizontal or if there is no more compressed air on board, as in Fig. 2, it will be possible to flood from the floor all the compartment 6, as high as the lower edge of the plate 1, filling up the tube 7 and the trunk 3, so that all men will be enabled to escape and emerge. This is exactly the case of the well known Holland tube.

On the contrary, when the compartment 6, as in the most general case, is not liable to be flooded, nor to spoil electric cables and machinery, nor to develop hydrochloric acid from the battery cells, while rescuing another sunken submarine or just to make an ordinary training practice for men, it will be enough to install a second plate 10, to be cleared off like the plate 1; and which, only when necessary, is to be made watertight, by any well known contrivance, to the cylindrical edge of the circular or elliptical iron plate 11; thus forming a tub 8, where the free water level will lie below the air-pressure of the room 6.

Figs. 4, 5, 6 and 7 show only one of the numerous contrivances which may be applied to obtain, when necessary, a quick and water-tight mounting of the plates 1 and 10 on their supports 20 and 11, and following their cylinder generating line.

Figs. 4 and 5 show in effect how to fasten together these plates, by catching the edge 14 of the plate on its other edge 15, using small bolts 12, whose heads are fixed to the butt-plate 13, soldered to the edge; rubber packing 16 being pressed between edges 13 and 14. The rubber packing and the bolts stop at point 17 of the plate 18; which is therefore of a uniform thickness from 17 to 18. The same jointing of plates 1 and 10 could obviously be obtained by a great many other well known contrivances.

As for the jointing of cylinders 1 and 10 to their supports 20 and 11, it will be enough (Figs. 6 and 7) to introduce their edges 18 into the rifles of their supports; to fill up, all around inside the tubes, with rubber or asbestos packings; and to force from the outside by hammering on the specially shaped rings 22. The same joints could obviously be obtained in a great many other ways.

Claims:

1. In combination with a submarine turret, a door permitting ingress into the turret, another door permitting egress from the turret, a wall member extending across the whole width of the turret and attached to the floor thereof and extending upwardly a distance less than the height of the turret, a second

wall member extending across the whole width of the turret and attached to the roof thereof and extending downwardly a distance less than the height of the turret, said doors lying within the chambers defined by 70 said walls.

2. A submarine turret as set forth in claim 1, means for maintaining water therein at a level such that flooding of the turret is avoided.

3. In combination with a submarine turret and a compartment of the submarine, a collapsible tank fastened to the floor of said compartment, a collapsible tube extending between said tank and said turret, said tube in 80 either its extended or collapsible position being without the turret, and means providing water tight connections between one end of said tube and the floor of the turret, and between said tank and the floor of the compartment.

4. A structure as set forth in claim 3, wherein the water tight connections consist of rings forcing the edges of the tube against packing material within supports.

5. In combination with a submarine vessel, a chamber permitting egress from said vessel, a second chamber between said vessel and said first chamber, collapsible connecting means between said chambers, and collapsible means permitting the flooding of said first chamber and preventing flooding of said second chamber.

In testimony whereof I affix my signature.

ANGELO BELLONI.
